UNITED STATES PATENT OFFICE.

JOHN L. KEILMAN, OF DYER, INDIANA.

DESIGN FOR A STICK-PIN.

No. 39,135.

Specification for Design.

Patented Feb. 18, 1908.

Application filed January 7, 1908. Serial No. 409,721. Term of patent 3½ years.

To all whom it may concern:

Be it known that I, JOHN L. KEILMAN, a citizen of the United States, residing at Dyer, in the county of Lake and State of Indiana, have invented a new, original, and ornamental Design for Stick-Pins, of which the following is a specification, reference being had to the accompanying drawing, forming part thereof.

The figure is a perspective view of a stick pin, showing my new design.

I claim:

The ornamental design for a stick pin, as shown.

JOHN L. KEILMAN.
